Stephen Shubrick, Wachusett, Mass.

Letters Patent

The subscriber is the true Author of the above Letters Patent and making part of the same containing a description in the name of the late Stephen Shubrick himself of his Improvement in that part of the "Nail Mail Machine," called the "Nipper," which gives the nail a motion as it is taken from the cutter.

To all persons to whom these presents shall come. Stephen Shubrick of Wachusett in the County of Plymouth and State of Mass - a witness. I entreat you kindly putting

I doth know that the said Stephen Shubrick have invented, constructed and applied to use a new and useful Improvement in that part of the "Nail Mail Machine," called the Nipper, specified in the kind following viz. This Improvement consists in having the Nipper to play upon a pin in the upright post through which it passes and is therefore called a joint Nipper, which admits of a vertical as well as a horizontal movement a description being taught for by those engaged in the business of making Nails from the machine aforesaid. This joint in the Nipper together with the mode of applying a weight or spring to the back arm of the lever to regulate its motion constitutes the Improvement in which he claims an exclusive property: & a reference to the different parts of this machine will serve to illustrate the utility of the Improvement of which he claims the invention.

- A is called the bed piece
- B Heading Lever
- C Cutting Lever
- D Griping Lever
- E Ayle
- F The lower Wheel
- G Nipper Lever H The clipper rock

passes through the opposite part and instead of using three or four as formerly which is a great bulk of the horizontal movement it is allowed to play in a few which makes a joint by means of which a Horizontal as well as a Horizontal Motion is produced. By this new and improved arrangement it takes the nail from the cutters as it goes down to be beaten and instead of driving it against the back since it strikes it in such a manner upon the edge as to give it the turn of a quarter of a circle even then by its vertical Motion catches it upon the under side when it is gript firmly & held fast to receive its head. This has been found by long & many experiments not only by him self but by others well acquainted with the business of making Nails by machinery to be a very valuable improvement on the Machine aforesaid. It is capable also with its weight or spring to be applied to other Machines but whether with the same advantage as to the "Hand Machine" he cannot say with the same degree of certainty as he has not had an opportunity of putting it to the test. The general improvement however in the Nipper by which the Central Motion as formerly mentioned is produced that is by having it play in the first making thereby a joint and having its Motion regulated by a weight or spring attached to its shottet arms he claims as his invention whether applied to "Needle Nail Machine" or any other and in this he claims an exclusive property. In testimony that the above is a true Specification of my improvement as above described I have sworn let my said this tenth day of July in the Year of our Lord one thousand eight hundred and thirty four.
